UNITED STATES PATENT OFFICE

RAYMOND W. STORM, OF PELHAM MANOR, NEW YORK

SOUND AND HEAT INSULATED FLOORING

Application filed May 2, 1931. Serial No. 594,681.

The invention relates to flooring and has as an object the provision of a flooring that will be quiet in use both as regards the apartment wherein the material is laid and an apartment therebelow.

It is a further object of the invention to provide a floor material that may be prepared at the factory and very rapidly laid.

It is a further object to provide a construction of floor element that lends itself readily to factory production and which makes possible the utilization of short lengths of material.

Further objects of the invention will appear from the following description when read in connection with the accompanying drawings showing illustrative embodiments of the invention, and wherein:

Fig. 1 is a bottom plan view of an element provided by the invention which may be assembled with other similar elements to form a floor;

Fig. 2 is a section on line 2—2 of Fig. 1;

Fig. 3 is a vertical transverse section of three assembled elements such as shown in Figs. 1 and 2;

Fig. 4 is a bottom plan view of a modified form of element;

Fig. 5 is a section on line 5—5 of Fig. 4;

Fig. 6 is a transverse section of a further modification;

Fig. 7 is a bottom plan view of a still further modification; and

Fig. 8 is a detail section on line 8—8 of Fig. 7 to an enlarged scale.

As shown in Figs. 1 to 3 inclusive, the floor is formed of a wearing surface layer element 10 desirably formed of wooden elements each having a tongue 11 at one edge and being grooved as at 12 upon the remaining three edges. The lower surface of the wearing layer is shown as rabbeted at the back as indicated at 13 and a resilient bearing element 14 is shown as provided with an upstanding rib 15 to fit the rabbet 13 in the wearing layer. The surface of the element 14 is coated with glue before being applied to the wearing layer 10 and the rib and rabbet joint between the elements serves to guide the two parts into proper relation when assembled.

As is usual with flooring the portion below the tongue 11 and also below the grooves 12 sets back of the plane of the portion 16 above the tongue and grooves to ensure that the joint at the surface of the flooring shall be tight.

To assist in securing the element 14 to the element 10, there are shown driven fastening elements 17 which, in addition to their securing function, have another function to be explained below.

The bottom of the assembled elements as 18 and the edges of the same as 19, as well as the edges of the wearing layer 10, are coated with an integral layer of cementitious or bituminous material, as asphalt. The said layer is desirably applied at the time of laying the floor by dipping the elements into a pan of hot material and immediately placing the same upon the subfloor, thereby cementing the assembled elements to the subfloor as well as increasing the strength of the elements in a manner also to be explained hereinafter.

In the form of the invention of Figs. 4 and 5 the bearing elements are shown in the form of frusto-conical or cylindrical members 20 seated in correspondingly shaped recesses 21 in the non-wearing surface of the wearing layer, and the lower exposed surface of the wearing layer 10 of this form of the invention, the vertical surfaces of the elements 20, and the bottom surfaces thereof are also coated with cementitious material, which material is carried up around the edges of the wearing surface layer elements as at 22.

In the form of the invention of Fig. 6, the wearing surface layer 10 is formed as in Figs. 1 to 3 inclusive but the bearing material 23 is shown as rectangular in cross-section and does not extend below the portions 24, 25, of the wearing surface element. In this form of the invention also driven elements 17 are indicated and the cementitious layer 18 is also applied about the entire lower surfaces of the assembled flooring element.

In the form of the invention of Figs. 7 and 8, the rabbets in the non-wearing surface of the elements 10 are shown as transverse, two rabbets being indicated in each of the sur-

face elements, although of course it is obvious that more than two may be used. In this form of the invention, there is indicated a plurality of surface elements 10 held in assembly by the bearing material 26 seated in the transverse rabbets 27 and extending continuously across the assembled elements. It is obvious that the elements 26 in this form of the invention may extend across one only of the elements 10 and that the elements 10 may then be separately assembled upon the floor in the same manner as indicated in Fig. 3. In this form of the invention also driven elements 17 are indicated.

15 The bearing material 14, 20, 23, and 26 may be formed of a wide range of materials as, for instance, cellulose fibre wallboard, rubber, balsa wood, linoleum, cork either natural or molded cork composition, or any resilient 20 spongy composition. In the form of the invention of Figs. 1-3 and 6-8 inclusive, it is at present preferred to use cellulose fibre wallboard material, as this material is readily available and very suitable for the purpose.

25 The form of the invention of Figs. 4 and 5 lends itself admirably to the use of ordinary cork such as used for bottle stoppers.

30 A defect of former floors of the nature of the present invention which have been laid with cellulose fibre wallboard material has been that the wallboard adheres perfectly to the subfloor when laid in bituminous material and the surface of the wallboard also adheres to the wearing surface layer by being glued thereto but when upward strain comes upon the upper surface layer caused, for instance, by swelling of the floor and consequent tendency to upward bulging of the surface, the wallboard material splits parallel with its 35 surfaces, having little strength to resist such splitting. In the flooring of the present invention such splitting is resisted by two features of the construction; first, by the coating of the edges of the material with the bituminous material as indicated at 19, Fig. 3, which greatly strengthens the bearing surface layer made up of the assembled elements from such splitting due to the fact that many vertical ribs 19 are thus provided throughout the entire floor area, and, second, by the presence of the fastening elements 17. Another defect in former floors of this character has been that the entire floor surface of a room acts as a diaphragm vibrating with resonance to transmit the sound of any blow thereon, as produced by a footfall. The presence of the driven elements 17 acts as an effectual damper to such vibration and flooring of this character which has been laid and tested in service discloses the fact that because of these driven fastening elements, the completed floor is much more quiet than floors formerly provided.

65 When wood is used, the flooring utilizes

short lengths of the material and is therefore very economical to produce.

The presence of the recesses in the non-wearing surface of the wearing layer engaging projecting portions of the bearing material has the function in use of anchoring the surface layer to the bearing layer in such manner that lateral displacement of the surface layer under expansion and contraction carries with it the adjoining portion of the bearing layer thus greatly increasing the strength of the flooring in service.

70 The cementitious layer 18 has the function not only of causing adherence of the flooring to the subfloor thereby doing away with the necessity of nailing the flooring down but also prevents access of moisture to the bearing layer which would rapidly cause the same to deteriorate.

75 The consequent avoidance of the necessity of nailing the flooring down also greatly improves the sound insulation of the floor, as in former insulated floors where the floor was nailed to the subfloor through the bearing layer each nail acted as a rigid column to transmit sound vibrations to the subfloor and thus to the apartment below and the sound insulation of the bearing layer was in these former constructions very largely lost because of this fact.

80 In the foregoing description the main emphasis has been placed upon the sound deadening function of the invention. In addition to this function, the nature of the materials used and the construction disclosed secure valuable effects in heat insulation.

85 The word "cementitious" in the appended claims is used as a generic term including bituminous material as asphalt which is the material at present preferred.

90 Minor changes may be made in the physical embodiments of the invention within the scope of the appended claims without departing from the spirit thereof.

I claim:

1. A flooring element comprising, in combination, a wearing surface layer element having a recess in its non-wearing surface, a resilient bearing element having a portion projecting into said recess and its vertical edges set back from the adjacent edges of the wearing layer, and a layer of cementitious material covering the bearing surface and exposed edges of said bearing element.

11 2. A flooring element comprising, in combination, a wearing surface layer element having a groove extending across its non-wearing surface, a resilient bearing layer element united to said wearing layer and having a portion extending into said groove and its edges set back from the corresponding edges of the first named element, and a coating of cementitious material covering the lower surface of the assembled element and

the lower portions of the exposed edges thereof.

3. A flooring element comprising, in combination, a wearing surface layer element having a groove extending across its non-wearing surface, a resilient bearing layer element of compressible fibrous material united to said wearing layer and having a portion extending into said groove, and driven fastening elements projecting through the bearing layer into the wearing surface layer.

4. A flooring element comprising, in combination, a wearing surface layer having a groove extending across its non-wearing surface, a resilient bearing element of compressible fibrous material having a portion extending into said groove and a bearing portion adapted to space said wearing element from a supporting surface, and driven fastening and vibration-dampening elements extending through said bearing element into said wearing element, said fastening elements formed with heads, said heads sunk into the bearing surface so as to be out of contact with a supporting surface.

5. A flooring element comprising, in combination, a wearing surface layer having a groove extending across its non-wearing surface, a resilient bearing element of compressible fibrous material having a portion extending into said groove and a bearing portion adapted to space said wearing element from a supporting surface, driven fastening and vibration-dampening elements extending through said bearing element into said wearing element, said fastening elements formed with heads, said heads sunk into the bearing surface so as to be out of contact with a supporting surface, and a coating of cementitious material covering the exposed surfaces of said bearing layer and the heads of said fastening elements.

6. A flooring element comprising, in combination, a wearing surface layer having a tongue and grooves at its edges, the portions below said tongue and grooves setting back from the planes of the portions thereabove, a resilient bearing surface element of compressible fibrous material secured to the non-wearing surface of said wearing layer with its edges setting back from the planes of said first named portions of the wearing layer, and a coating of cementitious material covering the exposed surfaces of said bearing layer and extending over a portion of said first named portions.

7. A flooring element comprising, in combination: a wearing surface layer element; a resilient bearing layer element of less superficial extent than the wearing element with its edges set back from the corresponding edges of the first named element to provide for a layer of cementitious material to be applied to said set back edges and to be concealed from the surface of assembled ele-

ments in a floor; and driven fastening and vibration dampening elements passing through the bearing element into the wearing element with heads sunk into the surface of the bearing element to be out of contact with a foundation upon which a plurality of said flooring elements may be assembled.

8. A floor comprising a plurality of assembled elements each element comprising a wearing layer and a resilient bearing layer with its edges set back from the corresponding edges of the wearing layer element and united to the wearing layer element by driven fastening elements passing through the bearing element into the wearing element with heads sunk into the surface of the bearing element to be out of contact with a foundation, the lower surfaces of the bearing layer elements and each of said set back edges thereof coated with mastic whereby to provide a plurality of vertical ribs of mastic integral with a layer thereof extending over the lower surface of the assembled elements, said ribs extending upwardly into the lower portion of the assembly through the assembled resilient bearing layer of the floor.
